TRANSLUCENT HANDLE FOR PLUMBING FIXTURE OR THE LIKE

Marvin J. Smalley, Encino, Calif., assignor to Price-Pfister Brass Mfg. Co., Pacoima, Calif., a corporation of California

Filed Oct. 8, 1965, Ser. No. 87,376

Term of patent 14 years

(Cl. D91—3)

FIG. 1.

FIG. 2.

FIG. 4.

FIG. 3.

FIG. 5.

FIG. 6.

FIG. 7.

FIG. 8.

FIGURE 1 is a side elevational view of a translucent handle incorporating the present invention;

FIG. 2 is a top plan view of the handle shown in FIG. 1;

FIG. 3 is a sectional view taken a plane indicated by line 3-3 of FIG. 2;

FIG. 4 is a sectional view taken along a plane corresponding to line 4-4 of FIG. 3;

FIG. 5 is a side elevational view of a modified translucent handle structure;

FIG. 6 is a top plan view thereof;

FIG. 7 is a side elevational view of handle corresponding to that illustrated in FIG. 1; and

FIG. 8 is a plan view taken along a plane corresponding to line 8-8 of FIG. 7.

The elements shown in broken line are included for illustrative purposes only.

I claim:

The ornamental design for a translucent handle for plumbing fixture or the like, substantially as shown and described.
